DISPLAY STAND

William B. West, Canajoharie, N. Y., assignor to
Beech-Nut Packing Company, Canajoharie,
N. Y., a corporation of New York

Application March 6, 1937, Serial No. 129,364

2 Claims. (Cl. 211—128)

My invention relates to display stands, and has special reference to such stands that are particularly adapted for displaying packages of fruit drops, chewing gum and other confections.

5 The principal object of the invention is to provide a stand of the character indicated, which is of simple, strong and durable construction, which is capable of attractively displaying a large number of articles to the best advantage, and which is convenient in use.

10 Referring to the drawings,

Figure 1 is a view in perspective of my improved stand in its preferred form;

Fig. 2 is a side elevation;

15 Fig. 3 is a longitudinal sectional view, taken substantially on the line 3—3 of Figs. 1 and 4;

Fig. 4 is a front sectional elevation of the stand;

Fig. 5 is a perspective view, partly in section, of the upper left corner portion of the stand; and

20 Figs. 6, 7 and 8 are respectively detail longitudinal sectional views of individual supports for the articles to be displayed, articles of different shapes being shown by dot and dash lines arranged on the supports.

25 My improved display stand as illustrated in the drawings, is provided with longitudinal side walls 2 which are connected at their front ends by a front wall 4, and are further connected by an angle brace 6 extending between the lower 30 rear corners and by a brace 8 extending between the central portions of their lower edges.

Extending between the upper portions of the side walls are a plurality of supporting members 10 each having its ends turned downwardly to provide flanges 12 that are secured by rivets 14 to the side walls, said members 10 being arranged one behind the other. Each supporting member 10 is bent transversely thereof to provide a central support or shelf 16, and shelves 18 at opposite sides of the central shelf and stepped downwardly therefrom and from each other toward the side walls. The corresponding shelves 16 and 18 of the several members 10 are successively stepped upwardly from the front to the rear of the stand. The outermost shelves 18 are arranged below the outer edges of the side walls, and the central shelves 16 are above said edges. The portions of the side walls arranged adjacent the foremost member 10 have inwardly and upwardly bent portions 20 and downwardly bent portions 22. Also there is shown a filling strip 18' positioned a distance above the shelves 18 at each side of the central shelf 16 of the foremost supporting member 10. These filling strips may

be used when the foremost shelves 18 are too low to properly display certain articles.

The forward edges of the members 10 are arranged adjacent vertical walls 24 which have their ends secured to the side walls of the stand. Said walls 24 also are secured to the members 10 by means of inwardly turned flanges 26 thereon and rivets 28.

Partitions 30 of glass are supported against the forward sides of the walls 24. The foremost glass 10 partition 30 has its lower edge resting upon an angle support 32 secured to the side and front walls of the stand and the partition is held between the wall 24 and the front wall 4 of the stand. Each of the other partitions 30 is supported against the wall 24 by means of an angle member 34 secured to said wall 24. The three foremost supporting members 10 have their rear edges arranged adjacent the forward sides of the glass partitions 30. The partitions 30 may be 20 easily removed and replaced for cleaning purposes.

At the rear of the stand there is a member 36 secured between the side walls and adjacent the rear edge of the rearmost member 10. The upper 25 portion 38 of this member 10 is bent outwardly to provide a space between this member and the rear edge of the rearmost member 10 to receive a mirror 40, the mirror being removably held in position by means of channel members 42 secured 30 to the member 36.

The partitions 30 and the mirror 40 extend a distance above the supporting means provided by the stepped members 10, and their upper edges each preferably has a horizontal central portion 35 and downwardly and outwardly inclined portions so as to conform somewhat to the shape of the supporting members 10.

The component parts of the stand with the exception of the partitions 30 and mirror 40 may be 40 made of sheet metal.

Various sizes and shapes of small packages 41 of chewing gum, confections, and the like, may be conveniently supported on the step-like supports or shelves 16 and 18 as illustrated in Figs. 45 6, 7 and 8. When thus placed on the stand they are displayed to the best advantage, and may be conveniently removed by the purchasers without materially altering the attractiveness of the display as a whole. Owing to the raised arrangement of the central supports or shelves and the downwardly stepped supports or shelves at opposite sides of the central shelves, all of which are arranged in symmetrically stepped relationship, the articles to be displayed when the stand 50 55

is full has the appearance of one mass of more or less uniformly arranged packages that are heaped up centrally and transversely of the stand. This not only makes an attractive display but the packages are displayed to the prospective purchasers from all angles to the best advantage.

As will be evident to those skilled in the art, my invention permits various modifications without departing from the spirit thereof or the scope 10 of the appended claims.

What I claim is:

1. In a display stand of the class described, longitudinal side walls, supporting means for the articles to be displayed arranged between the side walls, said supporting means being divided

into sections arranged one behind the other, partitions arranged between and projecting above said sections and extending between the side walls, each section having a step-like support arranged centrally thereof and extending between the adjacent partitions, and having other step-like supports successively stepped downwardly from said central support toward said side walls, and the corresponding supports of the several sections being stepped upwardly from the front 10 toward the rear of the stand.

2. A structure according to claim 1 in which each of said supports is substantially flat and is inclined slightly upwardly and rearwardly.

WILLIAM B. WEST. 15
